UNITED STATES PATENT OFFICE.

SYDNEY CROSBIE, OF NEW BARNET, ENGLAND.

CENTRIFUGAL SPRAY-PRODUCER.

1,149,810.

Specification of Letters Patent.

Patented Aug. 10, 1915.

Application filed April 2, 1913. Serial No. 758,515.

To all whom it may concern:

Be it known that I, SYDNEY CROSBIE, a subject of the King of Great Britain, residing in New Barnet, England, (whose 5 post-office address is The Chestnuts, New Barnet, in the county of Herts, England,) have invented certain new and useful Improvements in Centrifugal Spray-Producers, of which the following is a specification.

10 The object of this invention is the spraying of oil and the like by centrifugal action for the purpose of being combined in its attenuated state with low pressure air so as to produce a combustible mixture for use in 15 furnaces and the like.

The invention will be more fully described by reference to the accompanying drawings in which—

Figure 1 is a longitudinal section of the 20 spraying device. Fig. 2 a longitudinal section of a modified construction and Fig. 3 a longitudinal section of a modification in the form of the cone.

The oil to be sprayed is fed into the pipe 25 *a* either by gravitation or by a force pump, this pipe being constructed with a coned exit end *b* either integral therewith or screwed into or on to the pipe *a*. The pipe and its cone is caused to revolve rapidly by 30 mechanism external to the gas producer. Owing to the rapid revolution the oil travels in the direction of the arrows clinging to the walls of the pipe owing to the centrifugal action, and as it emerges from the pipe 35 *a* into the cone *b*, the centrifugal action causes the oil to cling to the walls of the cone as indicated by the arrows until it reaches the lip of the larger mouth of the cone from which it is thrown off into the 40 chamber by centrifugal action in a thin film provided the edge of the cone is made straight, as shown in Fig. 2, and is therefore in a suitable condition for mixing with the air surrounding it in the carbureting 45 chamber. It is preferred, however, to make the edge of the cone in the form shown in Fig. 1 of the drawings or in the modified form shown in Fig. 3.

As shown in Fig. 1, the outer edge of the 50 cone is made with sharp points *b'* leaving flat portions of edge *c* between them and as shown in Fig. 3 the edge of the cone may be serrated so as to form sharp points *b'* the bottoms of the serrations forming acute 55 angles *c'*.

As the oil travels up the cone *b* from the

pipe *a* owing to the centrifugal action due to the rapid revolution of the pipe and cone it is thrown off in a thin film at the edge *c* or bottom of the serrations *c'* and along the 60 edges of the serrations. The sharp edges of the points *b'* or of the serrations traveling at great speed pass rapidly through this thin film of oil beating and cutting it and thus breaking it up into very minute particles, practically forming it into vapor.

Fig. 2 shows a method of performing the same operation of spraying by means of a reversed cone *b*. In this case the oil fed into the pipe *a* passes out from the pipe into a 70 chamber *e* formed in the interior of the cone *b* and thence through holes *d* surrounding the inner boss by which the pipe *a* is connected to the interior of the cone in the direction shown by the arrows, whence it 75 travels on to the walls of the cone. The pipe and cone being revolved at a high rate of speed throws the oil from the outside of the mouth of the cone into a thin film, when the edge of the cone is straight as shown or 80 as spray when the edge of the cone is provided with sharp points or is serrated, as previously described.

Having thus described the nature of this 85 invention and the best means I know of carrying the same into practical effect, I claim:

1. In spraying apparatus for oil and the like, a pipe rotatable about its own axis and into which the oil is fed for delivery to a 90 furnace or the like, and a spraying nozzle having an internally coned surface and an axially directed open discharge end, said nozzle being detachably supported from and in a manner to be rotated by the pipe, and 95 being axially alined and positioned relatively to the pipe so that oil is delivered from the pipe directly into the internally coned nozzle at its smaller end and is thrown outward from the edge of its larger or discharge end by centrifugal force as the pipe is rapidly rotated, said edge being constituted by a single surface of revolution and formed with a plurality of sharp projecting points, substantially as described. 100

2. In spraying apparatus for oil and the like, a pipe rotatable about its own axis and into which the oil is fed for delivery to a furnace or the like, and a spraying nozzle detachably supported from the forward end 110 or discharge end of the rotatable pipe, said nozzle having an internally coned surface

2
terminating in a closed or imperforate front end and being axially alined and positioned relatively to the pipe so that the discharge ends of the pipe and the coned nozzle are 5 oppositely directed and oil is delivered from the pipe directly into the internally coned nozzle and is discharged outwardly from the edge of its larger or discharge end by centrifugal force as the pipe is rapidly rotated, said edge being constituted by a single surface of revolution and formed with 10 a plurality of sharp projecting points.

3. In spraying apparatus for oil and the like, a pipe rotatable about its own axis and 15 into which the oil is fed for delivery to a furnace or the like, and a spraying nozzle having an internally coned surface and an axially directed open discharge end, said nozzle being detachably supported from and

in a manner to be rotated by the pipe, and 20 being axially alined and positioned relatively to the pipe so that the outlet ends of the pipe and coned nozzle are oppositely directed and oil is delivered from the pipe directly into the internally coned nozzle at its 25 smaller end and is thrown outward from the edge of its larger or discharge end by centrifugal force as the pipe is rapidly rotated, said edge being constituted by a single surface of revolution and formed with a plurality of sharp projecting points, substantially as described.

In testimony whereof I have signed my name to this specification in the presence of one subscribing witness.

SYDNEY CROSBIE.

Witness:

WALKER J. SKERTEN.
